GERSTEIN & BORUN LLP

(57) **CLAIM**

The ornamental design for a drawer guide plate, as shown and described.

DESCRIPTION

FIG. 1 is a rear perspective view of a drawer guide plate showing the new design in use with unclaimed environment; FIG. 2 is a rear perspective view of the invention illustrated in FIG. 1;

FIG. 3 is a front perspective view of the invention illustrated in FIG. 1;

FIG. 4 is a front view of the invention illustrated in FIG. 1; FIG. 5 is a rear view of the invention illustrated in FIG. 1; FIG. 6 is a right side view of the invention illustrated in FIG. 1;

FIG. 7 is a left side view of the invention illustrated in FIG. 1;

FIG. 8 is a top view of the invention illustrated in FIG. 1; and,

FIG. 9 is a bottom view of the invention illustrated in FIG. 1.

The broken lines in the drawings depict portions of the drawer guide plate that form no part of the claimed design. The additional broken lines in FIG. 1 depict environmental subject matter that forms no part of the claimed design.

1 Claim, 5 Drawing Sheets
